UNITED STATES PATENT OFFICE

HARRY LANDSIEDEL, OF CINCINNATI, OHIO, ASSIGNOR, BY MESNE ASSIGNMENTS,
TO REMINGTON RAND INC., OF NEW YORK, N. Y., A CORPORATION OF DELAWARE

ADDING MACHINE

Application filed April 20, 1923. Serial No. 633,374.

This invention relates to printing-adding machines designed especially for co-operating with perforated record cards of the well known Hollerith type, in which the printing and adding records are indicated by suitably spaced perforations in said cards which are usually provided with a series of vertical rows of imprinted digits from 0 to 9 arranged in several vertical columns, 5 each of sufficient capacity to accommodate the required data. However, the printing on said cards is merely for the purpose of facilitating a proper locating of the perforations, and said printing may be omitted 10 without in any way interfering with the successful operation of the machine of the present invention.

The object of the present invention is to simplify tabulating machines of the well 20 known Powers and Hollerith types and the work to be performed thereon, by providing a compact unified adding machine not only capable of performing the work now done by such machines, but a much greater 25 variety of work of the same general character.

Machines of the kind now in use, as exemplified by the Powers and Hollerith types, 30 in so far as their adding and printing functions are concerned, comprise associated separate adding and printing groups, each of sufficient capacity to accommodate the maximum possible requirements of such a group unit, with the result that in normal operation 35 many of the adding and printing elements in any particular group unit will rarely be called into service.

This method of associating several separate full capacity adding and printing group 40 units for use in a single tabulating machine not only greatly increases the manufacturing cost of such machines but at the same time reduces their efficiency. It will be obvious to those skilled in the art that such machines must of necessity be more bulky and 45 at the same time less flexible than a single unified machine so constructed as to permit the operator himself to establish such a grouping of the several printing and adding 50 instrumentalities as occasion may war-

rant. It is also obvious that such a unified machine, because of its compactness, and the consequent compactness of the printed columns, will effect a considerable saving in paper and at the same time produce more 55 slightly and desirable records than machines of the type now on the market.

In illustrating a preferable exemplification of the principles of my invention I have used for performing the adding and printing functions the commercially well known Dalton mechanisms, with necessary changes therein, together with setting up mechanisms of the well known Powers type, with necessary changes therein; but it will be 60 obvious to those skilled in the art that other adding and printing mechanisms may be adopted and used without in any way departing from the spirit of my invention. 65

In using machines of the general character of the one to which this invention is directed, it is the usual practice to perforate 70 previously designed record cards at the proper digit in each ordinal row in the columns representing data to be printed and 75 added, or printed only, after which said cards are preferably automatically fed into the adding or tabulating machine in such a manner as to cause the holes thus punched to co-operate either through electrical contacts like that of the Hollerith type, or through mechanical means like that of the Powers type, with the adding or tabulating mechanisms to print and add the items indicated by the holes previously punched, or 80 to add only when printing is not required, or print only when adding is not required. 85

In such machines the perforated cards are fed into the analyzing portion thereof in 90 position to co-operate with a series of plungers or like mechanical, pneumatic or electrical devices in register with the rows of digits in the record card. Upon release of the entire group of plungers or other co-operative devices, those which are in alignment with perforations will co-operate effectively to actuate the required number of stops or other controlling mechanism in the printing and accumulating portions of 95 the machine to cause it to print and add the 100

items represented by the perforations, or print only as the case may be.

Cards for use in connection with machines of this character are usually perforated in such a manner as to provide columns which contain rows of digits representing numbers to be added and accumulated, and also columns of digits indicating dates, stock sizes and the like to be recorded but not added.

From the foregoing it will be seen that provision must be made for adjusting machines of the character under consideration according to some grouping scheme which will confine the adding and accumulating of numbers to the particular columns requiring such adding and accumulating; and at the same time the machine must be provided with mechanism to permit the operator at will to select those columns in which printing only is required.

It is evident that a column containing, for example, four rows of digits to be accumulated and totalized may require five or more adding wheels to accommodate the total of such column. Therefore, if the next higher-order adding wheel or wheels are simultaneously required for like service in an adjoining column, a proper functioning of the mechanism will be impossible.

In machines of the character now on the market, such as the Powers and Hollerith machines, effort has been made to meet the commercial requirements by arranging the series of separate and distinct adding and printing group units side by side with mechanism provided for enabling the operator at will to adjust an entire group-unit or units either for service in columns to be added and printed or for columns which require printing only. This adjusting by group-units is objectionable by reason of the fact that each group-unit must within itself afford the necessary number of mechanisms to meet the greatest possible requirements which may be imposed upon it, whereas, in the actual operation of the machine, any particular group-unit may be utilized to but a fraction of its maximum capacity, so that in the machine as a whole a large number of the printing and adding instrumentalities occasionally required to meet all possible contingencies would remain idle in any particular case. It is obvious, therefore, that the cost of building such machines is excessive, besides which the printing columns are widely spaced because of the provision of surplus idle mechanism, especially when small items are listed, which is objectionable.

Machines of this character are further objectionable in that they lack the necessary flexibility to permit the operator to utilize any group arrangement other than that specifically arranged for by the manufac-

turer, whereas, in the machine of my invention, the operator at will may arrange the individual adding and printing mechanisms into such combinations as may be desired, each individual adding and printing train of elements being adapted for use either in its full adding and printing capacity or in its printing capacity alone, as occasion may warrant. This result, in my machine, is accomplished by the use of cards in which each column to be added is associated on its left with a column which requires printing only, so that it is possible, in accumulating and storing totals, to utilize the adding wheels of the adjacent printing group which are not required for instant service in connection with the printing mechanisms with which they are associated. This arrangement makes it unnecessary to provide special surplus adding wheels to accommodate an extended total, and enables the several columns to be printed in close relation to one another, and imposes no limitation whatsoever upon the operator in the group-arranging of his mechanisms other than that of avoiding juxtaposed relation of two adding columns in cases where an extended total may result from the accumulation of items.

In the present machine, which in the form shown employs printing sectors, racks, and adding wheels, it will be understood that one each of such instrumentalities associated in the printing and accumulating of a single digit will be referred to as a printing and adding train, and with this understanding it is proper to state that the present invention marks a distinct improvement over earlier constructions, in that each train is a counterpart of every other, in construction, function and mode of operation, across the entire width of the machine, so that by a multiplication of trains, which lie in very close relation to one another, the capacity of the machine may be indefinitely extended, and that howsoever great may be the aggregate capacity of the machine, each train may be thrown into group arrangement with any other train, either for the purpose of printing and adding, or for the purpose of printing alone. That is to say, each train in the entire set may be adjusted to perform its full capacity of printing and adding, in which case the machine will present but a single printing and adding group; or each train may be adjusted to print only as a constituent in a single printing group, or, as is, usually the case, the entire series of trains may be divided into a number of groups, each group comprising as many trains as may be required, thereby affording a practically unlimited field of adjustment in group arrangement without restriction other than that of providing for the accommodation of an extended total.

In the drawings:

Figure 1 is a sectional elevation of the upper portion of an adding machine illustrating the features of the present invention:

Fig. 2 is a rear elevation of the same showing a key control for regulating the selection of the listing and recording groups of data;

Fig. 3 is a detailed side view of a fragment of the key control mechanism;

Fig. 4 is a detail of one of the cipher stops and associated digit stops;

Figs. 5 and 6 are details of the carrying mechanism in different positions of adjustment;

Fig. 7 is a detail of the mechanism for moving the adding wheels into and out of mesh with the racks in the normal position of adjustment;

Fig. 8 is a view of the same mechanism adjusted for a totaling and clearing operation; and

Fig. 9 is a front elevation of the same mechanism.

The present invention is shown as mounted upon a frame 10 which contains a plunger mechanism for direct co-operation with the perforated cards, of the general character shown in the Powers Patent No. 1,236,481.

The frame 10 supports a base 11 from which protrude a series of push rods 12 adapted to be elevated by those plungers of the entire number of plungers which are released through the perforations in the record card. It is evident that the push pins must correspond in number and arrangement with the plungers, and that a plunger and push pin must be provided for each potential perforation in the record card.

Immediately above such push pin is located a vertically slidable stop 13 mounted in a fixed frame 14, the upper ends of the stops being arranged in an arcuate line, as indicated in Fig. 1. In addition to the movable stops, a terminal series of fixed stops 15 is provided for ultimately arresting movements of any type carrier which is free to move to the ultimate position. These rows of stops are provided to control the extent of movement of a series of closely positioned uniformly spaced type carriers 16 of sector shape, which type carriers depend from and are freely mounted upon a rock shaft 17, each type sector being provided with a tail piece 18 which is engaged by a spring 19 secured at its lower end to a cross bar 20, the arrangement being such that when the type sectors are free to move around the shaft 17 as an axle they will move to the extent permitted by the rows of stops 13 with which the type sectors co-operate. Each sector is provided with a heel 21 arranged to engage with any stop in the corresponding row which may be elevated prior to the release of the bank of type sectors.

The release of the type sectors is effected by the withdrawal of a universal cross bail bar 22 which is carried between a pair of arms 23 rigidly secured to and adapted to swing with the shaft 17. The bail bar engages all of the tail pieces 18, and when elevated, as in Fig. 1, holds the sectors in retracted position.

Each type sector has associated therewith a rack bar 24 of sector shape, provided along its lower edge with a rack 25 adapted to be engaged by one of a group of uniformly and closely spaced adding wheels 26 mounted upon a continuously extending unbroken shaft 26^a (Fig. 5) the number of adding wheels being equal to the number of racks and type sectors. The racks, like the type sectors, are freely mounted upon the rock shaft 17 and are adapted to move with the type sectors when latched thereto by the mechanism now to be described. This mechanism comprises, for each type sector and rack, a stop pin 27 (Figs. 1 and 3) laterally extending from the rack bar and adapted to be engaged by a hooked latch member 28 pivoted at the point 29 to the associated type sector, and adapted to be held in depressed position by the tension of the spring 30.

The tail end of each latch member 28 occupies a position immediately above the forward arm 31 of a bell crank lever 32, a series of levers 32 being mounted upon a cross rod 33 carried between a pair of connected side plates 34 which constitute a swinging frame mounted upon a transverse shaft 35. The lower arm of each bell crank lever lies in a position to be engaged by a lug 36 upstanding from a sliding key bar 37 having at its end a finger button 38 containing a proper indicating numeral or sign. A depression of any key has the effect of rocking the associated bell crank lever against the tension of a spring 39 and elevating the associated latch 28 to unlatch the type sector from the associated rack bar, so that the sector only will move out under tension of the spring 19 when the handle of the machine is operated and the shaft 17 rocked. The pin anchoring the spring 30 to the type sector limits the downward movement of the latch 28 as the type sector rocks forward.

The keys 38 correspond in number to the number of rows of digits which the machine is designed to handle, as, for instance, forty-five rows, and the arrangement is such that the operator may depress the requisite number of keys required to effectuate a grouping of the mechanisms into adding and non-adding groups in conformity with the scheme observed in grouping the columns on the cards which the machine is designed to handle, subject to the requirement that the several adding groups must associate

with non-adding groups, which latter furnish the surplus adding wheels required in the total taking operations.

In order to hold the keys in depressed position, each key is associated with a detent 40 provided with a tooth 41 adapted to engage with notches 42 in the lower edge of the associated key. All of the detents are pivoted upon a cross rod 43, and each detent is held elevated by a spring 44, as best shown in Fig. 3. The arrangement is such as to hold the key in either the normal or depressed position of adjustment. In order to effect a restoration of all of the keys to normal position a cross bail bar 45 is provided, which overlies all of the detents, and is carried at opposite ends by a pair of swinging arms 46 which are pivoted upon the protruding ends of the cross rod 43, slots 47 being cut in the plates 34 to permit a swinging movement of the bail bar 45. A depression of the arms causes a retraction of the detents and a simultaneous release of all of the depressed key bars, which are restored by the tension of the springs 39 acting through the bank of bell cranks 32.

To secure and print a total, the following mechanism is utilized: A total link 48 (Fig. 1), is provided which is pivoted at the point 49 to a total lever 50 of bell crank formation, which total lever is pivoted on a shaft 51 and operated by a link 51a (Figs. 7 and 8). The rear end of the total link occupies a position immediately in advance of a stud 52 (see also Fig. 2), inwardly extending from the left hand plate 34, so that when the total lever 50 is thrust inwardly or rearwardly the frame comprising the plates 34 and all mechanism carried thereby will be rocked to the rear, thereby releasing such of the latches 28 as have been engaged and rocked by the depression of the respective keys. This release of the bell cranks will permit the associated latches 28 to fall, thereby latching together the entire group of rack bars with the associated type sectors, so that all of the rack bars will be prepared to move forward with the type bars in the taking of totals. The usual mechanism, shown in Figs. 7, 8 and 9 under the control of the total link is provided for lifting the bank of adding wheels into engagement with the racks on the forward stroke of the racks, so that each adding wheel into which a number has been introduced permits an advance of the engaged rack to the degree required to restore the wheel to zero position, as is usual in adding wheel construction, which mechanism will now be described.

The adding wheels 26 are mounted upon the shaft 26^a the ends of which are journaled within the free ends of a pair of swinging arms A freely pivoted upon a cross rod B suitably mounted within inner supporting plates C. The protruding ends of the shaft

26^a are provided with rollers D which rest upon cam plates E each having an elevation F so disposed that when brought to bear upon the rollers the adding wheels will be lifted into mesh with the corresponding racks. The cam plates E are pinned upon a shaft G. Each cam plate is acted upon by a spring H which normally holds the cam in such position as to bring the elevation F into contact with the corresponding roller D. The shaft G, at the left end thereof, has slidably mounted thereon a slide plate I provided with an upper slot J which embraces the shaft G and a lower slot K which embraces a stud L outstanding from the lower end of the cam plate.

The slide plate is also provided with an obliquely disposed slot M which receives a pin N inwardly extending from a three-way arm O which is pivoted upon the end of the shaft G outside of the slide plate. The arrangement is such that as the slide plate is depressed, it will turn the three-way arm in a clockwise direction from the position shown in Fig. 7 to the position shown in Fig. 8.

The three-way arm is provided with a lower pin P and an upper pin Q, the former being normally disposed as in Fig. 7, to be engaged by a shoulder R on a wipe pawl S carried by the free end of an arm T mounted upon the main shaft 57. The lower end of the wipe pawl is acted upon by a spring U which causes the free end of the wipe pawl to swing in substantially parallel relation with the arm T when the main shaft is rotated on the forward stroke of the handle. The wipe pawl is further provided with a shoulder V which co-acts with the pin Q on the return movement of the shaft.

The slide plate I is adapted to be depressed by the contact of the lower finger of a bell crank lever W mounted upon a shaft, the upper end of the lever being engaged by a pin Y carried by the total link 48. The arrangement of these parts is such that when the total link is moved to the rear (left in Figs. 7 and 8), the lower end of the bell crank lever W will act to depress the slide plate I from the position shown in Fig. 7 to the position shown in Fig. 8. This will have the effect, through the action of the diagonally depressed slot M and pin N of turning the three-arm lever clockwise from the position occupied in Fig. 7 to the position occupied in Fig. 8.

With the parts as in Fig. 7, when the main shaft is rotated clockwise (Fig. 7) on the forward stroke of the handle, the shoulder R of the wipe pawl will momentarily engage the lower pin P of the three-way lever, and impart a partial rotation thereto which will be imparted to the cam plates E, rocking them so as to bring the elevated portions of the cam away from the rollers

D which allows the adding wheels to unmesh from the corresponding racks on the forward stroke of the handle. On the rear stroke of the handle, the shoulder V on the wipe pawl will engage the upper pin Q on the three-arm lever and immediately lift the adding wheels into mesh with the rack so that on the return movement of the handle the amount set up will be accumulated. When the total is taken, with the parts adjusted as in Fig. 8, the pin P will have been lifted to a position such that the wipe pawl will swing under the stud on the forward stroke of the operating handle, allowing the adding wheels to remain in mesh with the racks on the forward stroke. The pin Q, however, in this adjustment, occupies a position such that upon the return stroke it will be engaged by the shoulder V of the wipe pawl and moved with it sufficiently to cause a reverse movement of the cams which will allow the rollers D to ride down onto the depressed forward edge of each cam, thereby disengaging the adding wheels from the racks during the return movement of the racks which will leave the machine clear. Near the termination of the handle stroke on such clearing operation, the cams, which have been rocked rearwardly, will be restored by the contact of a finger Z which swings with the arm U against a stop pin Z' on the left-hand cam, which stop pin with the cams adjusted for clearing, will lie within the return path of the finger and be engaged thereby.

The above parts are common to adding machines of the Dalton type and are not special to the present invention, so that further description thereof is deemed unnecessary.

When, however, an amount has accumulated in a group which exceeds the capacity of the wheels composing that group, then as the wheel of the highest order in that group turns from its 9 to 0 point in the listing on an item, the carrying pawl 52^a, (Figs. 5 and 6), of the rack bar immediately to the left of it, in a non-adding group, is lifted and the rack bar will move one step to the rear, causing the digit 1 to be carried over from the adding group into the next left adjacent adding wheel to be accumulated as the highest figure in the total in a manner conformable to the usual means provided in adding machines for the carrying of the accumulation from order to order, as, for instance, in the Hopkins Patent No. 1,039,130. Thus it is evident that the capacity of any adding group can be extended beyond the normal capacity of the wheels provided in that group, by arranging the various groups of data in columns which add and accumulate, and associated groups which record without accumulating.

It will also be observed that by latching

all of the rack bars in preparation for a total, each rack bar and associated sector is in condition to actively participate in the recording of a total. After a rack bar of a nonadding group has functioned to carry an excess amount into its accumulating wheel, it is necessary to restore the rack bar, which has moved back one place under the tension of a spring 53, to its normal position where it will be latched by the carrying pawl that functions with it. This is accomplished by two arms 54, (Figs. 1 and 2), which are freely pivoted at their upper ends on the shaft 17. The lower ends of the arms are connected by means of a transverse bail 55 just to the rear of the rack bars and sectors, where it is held retracted by a spring 56. Each time the main shaft 57 is operated the rock shaft 17 is rocked by means of a link 58 which is connected to an arm 59 on the shaft 17 and to the main shaft cam 60 at the point 61.

Each arm 23 on the shaft 17 is provided with a stud 62 so positioned that the respective studs will come in contact with the arms 54 just before the main shaft has completed its forward movement. This will have the effect of driving the bail 55 far enough on each operation of the main shaft so that it will come in contact with any rack bar which may have carried, as already described, and therefore effects a restoration of these abnormally positioned rack bars to a position where they will be latched by the carrying pawls 52^a in the manner shown in the Hopkins patent aforesaid.

Ordinarily the heels 21 of the type sectors will limit against a cipher stop 63, but upon the taking of a total these heels are under the control of the accumulating wheels, and means are provided for shifting all the cipher stops to the side and out of the way of the sector heels. To effect this result the following mechanisms are provided:

Each cipher stop comprises an upstanding portion of a plate 64 provided at its forward and rear ends with fingers 65 extending through the adjacent portions of the frame 14, which fingers serve as pivots permitting the lateral swinging of the plate. The rear ends of all of the stop plates are engaged by a slide bar 66 which is provided with an outstanding stop pin 67 adapted to be engaged by the beveled cam surface 68 of a cam block 69 mounted on a shaft 70, which carries an arm 71 provided at its free end with a roller 72 which is adapted to be engaged by the beveled under edge of a finger 73 which depends from the total link 48, so that as the total link is moved rearwardly in preparation for the taking of a total the arm 71 will be moved downwardly and the shaft 70 with the cam block will be rocked in such a manner as to cause the beveled surface 68 to bear against the pin 67 and

thereby move the slide plate and with it the rear ends of the stop plates to positions permitting the heels 21 to clear the cipher stops and advance to the point permitted by the adding wheels, which give up the accumulated movements, and restore to zero position.

In order to permit the type sectors to advance past the cipher stops in listing items, each cipher stop plate is shouldered as indicated in Fig. 4, and is spring pressed against a corresponding line of shoulders on the associated row of digit stops, so that the elevation of any digit stop will swing the cipher stop bar to the side and allow the heel of the associated sector to clear the cipher stop and advance until it encounters the digit stop.

After a total has been taken, and as the total link 48 moves forward to its normal position, springs 72^a, (Fig. 1), secured to the side plate 34 cause the key control assembly to move forward, and those keys which are depressed will again release the latches, so that the group arrangement of the mechanism will remain undisturbed by the taking of a total.

The operation of the machine may be briefly summarized as follows: In preparing the machine for recording and accumulating group operations, those keys are depressed which are necessary to divide the mechanism into associated adding and recording groups in conformity with the column arrangement of the perforated cards. Thereafter the operation of the released plungers which enter the perforations in the lower portion of the machine will effect a lifting of a corresponding number of digit stops in the stop carriage in group arrangement. Thereafter, upon the operating of the main shaft, all of the type sectors will move forward until arrested by the upraised stops, and the hammers will be fired and the items listed in group arrangement.

Upon the taking of a total those racks only will function which either co-operate directly with the adding wheels in an adding group or are brought into the accumulating operation to record a higher order than can be accommodated in the adding group.

It is obvious that the machine of my invention herein described accommodates practically an unlimited variety of group arrangements of the individual adding and printing trains, since each of the keys, forty-five in number more or less, individually controls the extent of the functioning of the train with which it is associated, which train can thus be adjusted to conform to the functional requirements of the particular group within which the train is included for the time being. That is to say, each train may be adjusted to utilize its full

functional capacity in adding and printing, or to utilize its reduced functional capacity where printing only is required, without, however, in any way interfering with the operation of the carrying mechanism in extending the total from order to order.

Although the mechanism illustrating one form of my invention has been described with particularity, it is obvious that many modifications may be introduced without departing from the principle of the invention. Thus, for example, in place of the push rods utilized for actuating the stops under the control of previously punched cards, other stop actuating mechanism might be utilized, either under the control of previously prepared cards or similar pre-recorded instrumentalities, or under the control of keys which may be individually operated to set the stops in the required positions according to a group arrangement conformable to the setting of the group keys 38.

It is not, therefore, the intention to limit the invention to one in which the stops are simultaneously set through the transference of a record previously impressed on a card or the like, since the features of the present invention are available for use in initial setting up of records in the stops themselves.

I claim:

1. In an adding machine, the combination of rows of digit stops, means for selectively projecting the digit stops, a type carrying member associated with each row of digit stops and adapted to be arrested by the projection of a stop, a rack member associated with each type carrier, a selectively and independently operable latch member adapted to releasably latch each type carrier to its associated rack member, and a separate key member for each of the latches for actuating each of the latches.

2. In an adding machine, the combination of rows of digit stops, means for selectively projecting the digit stops, a type carrying member associated with each row of digit stops and adapted to be arrested by the projection of a stop, a rack member associated with each type carrier, a selectively and independently operable latch member adapted to releasably latch each type carrier to its associated rack member, a separate key member for each of the latches for controlling the operation thereof, and means for removing an entire group of key members out of co-acting relation with their respective latches.

3. In an adding machine, the combination of rows of digit stops, means for selectively projecting the digit stops, a type carrier associated with each row of digit stops and adapted to be arrested by a projected stop in said row, a rack member associated with

each type carrier, a latch for latching together each type carrier with its associated rack member, a key for each latch adapted when pressed to actuate the latch, means for simultaneously restoring all of the pressed keys to normal position, and means for moving all of the keys out of co-acting relation with the latches.

4. In an adding machine, the combination of rows of digit stops, means for selectively projecting the digit stops, a type carrier associated with each row of digit stops and adapted to be arrested by a projected stop in said row, a rack member associated with

15 each type carrier, a latch for latching together each type carrier with its associated rack member, a key for each latch adapted when pressed to actuate the latch, means for simultaneously restoring all of the pressed keys to normal position, a bank of adding wheels one for each rack member, and a total taking device adapted when actuated to move the adding wheels into total taking relation with the respective racks and adapted to effect a latching together of all of the type carriers with their associated racks.

5. In an adding machine, the combination of rows of digit stops, means for selectively projecting the digit stops, a type carrier for each row of digit stops provided with a heel for arresting against a projected stop, a rack member associated with each type carrier, a latch for each type carrier and associated rack, a latch actuating member for each latch, a key engaging each latch actuating member, a movable frame carrying the latch actuating members and keys, and means for moving said frame to restore all the latches to engaging position without disturbing the key adjustments.

6. In an adding machine, the combination of rows of digit stops, means for selectively projecting the digit stops, a type carrier for each row of digit stops provided with a heel for arresting against a projected stop, a rack member associated with each type carrier, a latch for each type carrier and associated rack, a latch actuating member for each latch, a key engaging each latch actuating member, a movable frame carrying the latch actuating members and keys, and total taking devices adapted when moved to total taking position to move said frame with the parts carried thereby to effect a latching together of the respective type carriers and rack members without disturbing the key adjustments.

7. In an adding machine, the combination of rows of digit stops, means for selectively projecting the digit stops, a type carrier for each row of digit stops provided with a heel for arresting against a projected stop, a rack member associated with each type carrier, a latch for each type carrier and associated rack, a latch actuating member for each

latch, a key engaging each latch actuating member, a movable frame carrying the latch actuating members and keys, total taking devices adapted when moved to total taking position to move said frame with the parts carried thereby to effect a latching together of the respective type carriers and rack members without disturbing the key adjustments and means for simultaneously restoring all of the pressed keys to normal position.

8. In an adding machine, the combination of rows of digit stops, means for selectively projecting the digit stops, a cipher stop in alignment with each row of digit stops and adapted to be moved out of such alignment by the projection of any digit stop in said row, means for simultaneously moving all of the cipher stops out of aligned relation with the respective rows of digit stops, a movable type carrier for each row of digit stops adapted normally to stop against the associated cipher stop, a rack member associated with each type carrier, means for selectively releasing the rack members from the type carriers, a bank of adding wheels one for each rack member, each adding wheel being adapted to carry from a lower to a higher order, and total taking means adapted when actuated to bring each type carrier and its associated rack into latched relation, to move all of the cipher stops to non-stopping position and to bring the adding wheels into total taking relation with the respective racks.

9. In an adding machine, the combination of rows of digit stops, means for selectively projecting said digit stops, a movable type carrier for each row of digit stops adapted to be arrested by any elevated stop in such row, a rack for each type carrier, latching means for each type carrier and its associated rack for latching said members together to move in unison, key controlled means for selectively actuating said latches, a mounting for said key controlled means adapted to be moved to position to disengage the latch actuating devices from latch engaging position and to restore the latches to latching relation, a bank of adding wheels, one for each rack, each of said adding wheels being adapted to carry to the next higher order, total taking devices adapted when actuated to move the adding wheels into total taking relation with the racks and to move the latch actuating devices out of co-operative relation with the latches, and a universal bail adapted to restore all of the racks involved in carrying operations to normal position.

10. In an adding machine, the combination of rows of digit stops, means for selectively projecting a digit stop in each row, a pivoted type sector for each row of digit stops provided with a heel adapted to be

arrested by any projected stop in said row, a co-axially pivoted rack for each type carrier, a latch carried by each type carrier and adapted normally to latch said type carrier to its associated rack, a movable frame, a plurality of latch actuating devices carried by said frame, one for each latch, a plurality of keys carried by said frame, one for each latch actuating device, a bank of adding wheels, one for each rack, total taking devices adapted when actuated to move said frame to position to permit release of said latches and to bring said adding wheels into total taking relation with respect to said racks, means carried by said frame for restoring all of the keys to normal position, and means adapted to restore the racks to normal position after the taking of a total.

11. In an adding machine, the combination of rows of digit stops, means for selectively projecting the digit stops, type sectors mounted to oscillate in alignment with the respective rows of stops and each provided with an abutment adapted to be engaged by a projected stop in the associated row, a rack member for each type sector adapted to oscillate in unison therewith, a latch for each type sector and its associated rack and having an operative and an inoperative position, key controlled means for selectively positioning any desired latch or latches in one of said positions, and mechanism in connection with said key controlled means for simultaneously restoring all of said latches to the other one of their positions.

12. In an adding machine, the combination of rows of digit stops, means for selectively projecting the digit stops, type sectors mounted to oscillate in alignment with the respective rows of stops and each provided with an abutment adapted to be engaged by a projected stop in the associated row, a rack member for each type sector adapted to oscillate in unison therewith, a latch for each type sector and its associated rack and operative in its normal position effectively to latch its type sector to its associated rack, and independently and selectively operable key controlled means for selectively adjusting any desired latch or latches to position where they will be ineffective to perform the latching function.

13. In an adding machine, the combination of rows of digit stops, means for selectively projecting the digit stops, a type carrier associated with each row of digit stops and adapted to be arrested by a projected stop in said row, a rack member associated with each type carrier, a latch for latching together each type carrier with its associated rack member, a movable frame carrying keys, total taking devices adapted when moved to total taking position to move said frame with the parts carried thereby to

effect a latching together of the respective type carriers and rack members while the arrangement of the keys remains undisturbed, and means for simultaneously restoring all of the keys that had been operated to normal position.

14. In an adding machine, the combination of selectively operated setting up devices arranged in closely spaced rows, juxtaposed adding and printing trains, one for each row of setting up devices, and operable to a degree conformable to the positioning of the respective setting up devices, releasable means normally connecting the adding and printing elements of each train, and juxtaposed adjusting devices, one for each adding and printing train, for selectively moving said releasable means to disconnect the adding and printing elements of said train independently of any movement of the setting-up devices.

15. In an adding machine, the combination of selectively operated setting up devices arranged in closely spaced rows, juxtaposed adding and printing trains, one for each row of setting up devices and operable to a degree conformable to the positioning of the respective setting up devices, releasable means normally connecting the adding and printing elements of each train, juxtaposed adjusting devices, one for each adding and printing train, for selectively moving said releasable means to disconnect the adding and printing elements of said train, and means for restoring the adding element of each train from carry position to normal position during an operation of the machine in which said releasable means has been moved to disconnect the adding and printing elements.

16. In an adding machine, the combination of a plurality of adding wheels, carrying mechanism co-operatively related to said adding wheels to carry from order to order, actuating mechanisms for the adding wheels adapted normally to engage with and rotate the same, associate printing mechanisms normally attached to and co-operative with the said associated actuating mechanisms for printing numbers corresponding to the numbers introduced into the adding wheels, means adapted selectively to disconnect any predetermined number of adding wheel actuating mechanisms from the associate printing mechanisms, selectively operated setting up devices for regulating the extent of movement of the corresponding printing mechanisms, whereby any predetermined number of the printing mechanisms may operate independently of the associated adding wheel actuating mechanisms in the printing of numerical data not requiring addition, and means associated with the adding wheels for carrying from order to order and operable independently of the

connection or disconnection of the associated adding wheel actuating and printing mechanisms.

17. In an adding machine, the combination of a series of laterally adjacent closely spaced movable printing devices, a series of adding wheels, one for each of the printing devices, a series of adding wheel actuating devices, one for each of the printing devices and normally connected to and movable therewith, means for selectively disconnecting any predetermined number of the associated printing and wheel actuating devices, setting up means for selectively regulating the degree of movement of said associated devices when connected, and carrying mechanism operable through the conjoint action of the adding wheels and the adding wheel actuating devices for carrying from order to order independently of the connection or disconnection of said actuating devices with the associated printing devices, said means including a carrying pawl for each actuating device, adapted to be effectively moved at the proper time by the next lower-order-adding wheel, and adapted when moved to permit a carrying movement of the actuating device with which the pawl is associated.

30 18. In an adding machine, juxtaposed rows of setting up devices, an adding wheel for each row of setting up devices, a printing device for each row of setting up devices adapted to have its movements controlled thereby, an adding wheel actuating device associated with each printing device and normally movable therewith, a latch for normally connecting each printing device with its associated adding wheel actuating device, a movable frame, a plurality of latch actuating devices carried by said frame, one for each latch, a plurality of keys carried by said frame, one for each of the latch actuating devices, and total taking devices adapted when actuated to move said frame to position to permit release of said latches by the latch actuating devices and to bring said adding wheels into total taking relation with respect to the wheel actuating devices.

50 19. In an adding machine, juxtaposed rows of setting up devices, an adding wheel for each row of setting up devices, a printing device for each row of setting up devices adapted to have its movements controlled thereby, an adding wheel actuating device associated with each printing device and normally movable therewith, a latch for normally connecting each printing device with its associated adding wheel actuating device, a movable frame, a plurality of latch actuating devices carried by said frame, one for each latch, a plurality of keys carried by said frame, one for each of the latch actuating devices, total taking devices adapted when actuated to move said

frame to position to permit release of said latches by the latch actuating devices, and to bring said adding wheels into total taking relation with respect to the wheel actuating devices, and constantly operable carrying devices for the adding wheels.

5 20. In an adding machine, juxtaposed rows of setting up devices, an adding wheel for each row of setting up devices, a printing device for each row of setting up devices adapted to have its movements controlled thereby, an adding wheel actuating device associated with each printing device and normally movable therewith, a latch for normally connecting each printing device with its associated adding wheel actuating device, a movable frame, a plurality of latch actuating devices carried by said frame, one for each latch, a plurality of keys carried by said frame, one for each of the latch actuating devices, total taking devices adapted when actuated to move said frame to position to permit release of said latches by the latch actuating devices, and to bring said adding wheels into total taking relation with respect to the wheel actuating devices, constantly operable carrying devices for the adding wheels, and means carried by said movable frame for restoring all of the latch operating keys to normal position.

10 21. In an adding machine, the combination of a row of setting up devices, an adding wheel, a printing device adapted to contact with the row of setting up devices, an adding wheel-actuating-device associated with the printing device, an independently operable latch independent of the setting up devices for normally connecting the printing devices, a key controlled device for moving the latch to disengaging position, and a mounting for said key controlled device, adapted to be moved to position to effect a relatching of said latch by said latch moving device irrespective of the key adjustment of the latch moving device.

15 22. In a machine of the class described capable of printing and adding items and printing totals; the combination of adding racks, associated type carriers, means for adjusting the adding racks and their associated type carriers to the same extent, means for preventing an adjustment of any of said racks upon adjustment of its associated type carrier in item entering operations, and means for causing all of said racks to be adjusted to the same extent as their associated type carriers in total printing operations.

23. In a machine of the class described capable of printing and adding items and of printing the total thereof; the combination of adding racks and associated type carriers, means for selectively and individually controlling each adding rack and its associated type carrier to be adjusted to the same

extent or one to move independently of the other, and means for causing each rack and its type carrier to move the same extent during total printing operations.

24. In a machine of the class described; 5 the combination of adding racks and a type carrier for each rack; of means for selectively and individually disconnecting said adding racks from their associated type carriers during adding and listing operations, 10 and means for removing said disconnecting means bodily into an ineffective position.

25. In a machine of the class described capable of adding and listing items and printing their total; the combination of 15 adding racks, a type carrier for each rack, means for selectively and individually disconnecting said adding racks from their associated type carriers during adding and listing operations, a total control key, and 20 means operated by said key for removing said disconnecting means bodily into an ineffective position.
